(57) **CLAIM**

We claim the ornamental design for a headlight, as shown and described.

DESCRIPTION

FIG. 1 is an isometric view of the headlight of the present invention.

FIG. 2 is a front-elevational view of the headlight.

FIG. 3 is a rear-elevational view of the headlight.

FIG. 4 is a left side-elevational view of the headlight.

FIG. 5 is a right side-elevational view of the headlight.

FIG. 6 is a top view of the headlight.

FIG. 7 is a bottom view of the headlight.

FIG. 8 is an isometric view of the headlight; and,

FIG. 9 is an environmental isometric view of the headlight mounted in a snowmobile.

In FIGS. 1-8 The broken lines depict portions of the headlight and form no part of the claimed design.

In FIG. 9 the broken lines that depict a snowmobile are directed to environmental structure and form no part of the claimed design.
